UNITED STATES PATENT OFFICE.

OSCAR J. WATTS, OF KENSINGTON, KANSAS.

STENCIL.

1,202,626.

Specification of Letters Patent. Patented Oct. 24, 1916.

Application filed August 14, 1911. Serial No. 643,923.

To all whom it may concern:

Be it known that I, OSCAR J. WATTS, a citizen of the United States, residing at Kensington, in the county of Smith and 5 State of Kansas, have invented certain new and useful Improvements in Stencils; and I do hereby declare the following to be a full, clear, and exact description of the invention, such as will enable others skilled in the art 10 to which it appertains to make and use the same.

This invention relates to stencils and is designed to construct a device of this character which will simplify the marking of textiles in that the accurate placing of said 15 stencil may be assured.

A further object of this invention is to provide a means for preventing the slipping of the stencil during the marking of the 20 textile.

Heretofore in the marking of textiles, particularly in the hand designed goods, it has been necessary to use carbon or other copying paper beneath the paper on which the 25 design is impressed, whereas by the use of the present system the necessity of carbon or copying paper is absolutely eliminated and the outline of the design may be placed directly and accurately upon the textile.

30 With the above and other objects in view, the invention consists in the construction, combination, and arrangement of parts, all as hereinafter more fully described, claimed and illustrated in the accompanying drawings, in which,

Figure 1 is a top plan view of a stencil constructed in accordance with the present invention; Fig. 2 is a central longitudinal section thereof.

40 Reference being had more particularly to the drawings, 10 indicates a card-board of any suitable size pierced centrally by the design openings or apertures 11, said openings being of any size and formation. A 45 scale 12 is located at each transverse end of the board 10 and provides a means for the accurate spacing of the design from the edge of the textile and from the adjacent row of designs. Equidistant from the sides, both 50 longitudinal and transverse, of the card board 10 are the slotted openings 13 and 13'

which provide a means for accurately measuring the distance between each unit of design. Upon the under side of the card board 10 is glued or otherwise secured or attached 55 a sheet of sand paper or other rough material 14, which prevents the slipping of the stencil or card board 10 upon the textile. Sand paper, as is well known, is very tough and strong and when thus applied, greatly 60 reinforces the stencil.

From the foregoing, it will readily be understood that when it is desired to trace a design upon goods of any texture the board 10 is placed thereon, the distance of the same 65 from the edges of the goods being determined by the scales 12. The design openings 11 are then traced with a pencil or any other suitable implement and marks made through the lower slotted openings 13'. The 70 card board 10 is then moved until the slotted openings 13 correspond with the marks previously made through the slotted openings 13' after which the process is again repeated indefinitely. It will be also clearly 75 understood that in the practical manufacture of the device herein set forth, the same will be constructed of material having the lower side thereof sanded or otherwise roughened, it being unnecessary and impractical to construct the same with two sheets of material glued together, one sheet being 80 of sand paper or other roughened material.

Having thus described my invention, what I claim as new and desire to secure by Letters Patent is:

1. The herein-described stencil comprising an elongated upper layer of cardboard and an elongated lower layer of sandpaper, the layers being permanently connected together 90 with the sandpaper layer having its sanded surface lowermost, said layers having a stencil design cut therefrom and extending longitudinally thereof, and said layers being provided on both sides of the design with 95 transversely extending elongated openings, the openings on one side of the design being alined with the openings on the opposite side, and all of the openings being in alinement with the opposite ends of the design. 100

2. A stencil sheet having stencil openings and provided on its contact side with ad-

herent spaced granular particles adapted to engage without destroying a wet background of the surface to be stenciled and sufficient in number to hold the main body of the 5 stencil sheet out of contact with said wet background during the stenciling operation.

In testimony whereof I affix my signature in presence of two witnesses.

OSCAR J. WATTS.
